United States Patent Office

Des. 183,846
Patented Nov. 4, 1958

183,846

SOAP CAKE

Ralph E. Lippert, Cincinnati, Ohio, assignor to The Andrew Jergens Company, Cincinnati, Ohio, a corporation of Ohio

Application May 24, 1957, Serial No. 46,340

Term of patent 14 years

(Cl. D73—1)

Fig. 1

Fig. 2

Figure 1 is a top plan view of a soap cake showing my new design.

Figure 2 is a side elevational view thereof.

I claim:

The ornamental design for a soap cake, substantially as shown.

References Cited in the file of this patent

UNITED STATES PATENTS

D. 16,588	Smith	Mar. 28, 1886
D. 89,350	Mosheim	Feb. 28, 1933
D. 131,541	Stoner et al.	Mar. 10, 1942